UNITED STATES PATENT OFFICE.

EDWARD CHAS. BORCHERS, OF CHICAGO, ILLINOIS.

ARTICLES OF MANUFACTURE AND METHOD OF MAKING SAME.

1,326,639.

Specification of Letters Patent. Patented Dec. 30, 1919.

Application filed April 21, 1919. Serial No. 291,584.

To all whom it may concern:

Be it known that I, EDWARD C. BORCHERS, a citizen of the United States of America, and a resident of Chicago, county of Cook, 5 and State of Illinois, have invented certain new and useful Improvements in Articles of Manufacture and Methods of Making Same, of which the following is a specification.

This invention relates to articles of manufacture of an ornamental nature, and to methods of forming same, and particularly to methods of attaching plates of celluloid or the like to plates of metal.

The main objects of this invention are to 15 provide an improved structure for ornamental articles of manufacture, such as belt buckles; to provide improved means and methods for attaching plates of unlike character to each other, and especially, means 20 for attaching plates of readily cemented composite character to backing plates of metal. A further object is to provide a process whereby a celluloid plate may be secured to a metal plate by rigid metal fastening means in such manner as to present 25 an unbroken integral appearance. A still further object is to provide a method for ornamenting the face of the celluloid plate by attaching a decorative design thereto in 30 a substantially integral manner.

An illustrative embodiment of this invention is shown in the accompanying drawings, in which—

Figure 1 is a plan of a belt buckle embodying this invention, certain details immaterial to this invention being omitted.

Fig. 2 is a side elevation of said buckle.

Fig. 3 is a section on the line 3—3 of Fig. 2.

Fig. 4 is a section on the line 4—4 of Fig. 2.

Fig. 5 is an enlarged section on the line 5—5 of Fig. 1, showing the device in a partly finished state.

Fig. 6 is a fragmentary view of a section similar to Fig. 5, but showing the result of an additional step in the process of manufacture.

Fig. 7 is a section on the line 5—5 of Fig. 5, as the device appears when finished.

Referring to the structure shown in the drawings, the metal plate 1 has secured thereto a celluloid plate 2 which in turn has secured to its front side a face plate of celluloid 3, which is provided with a decorative device 4. The plate 3 is secured to plate

2 either with or without an additional intermediate plate of celluloid 5, which if used is of a different color designed to add to the artistic appearance of the device, for 60 instance, the plates 2 and 3 being white, and the medial plate 5 being black.

The device is preferably made oblong in shape, and the plate 1 is provided with stiffening side flanges 6, each formed medially 65 with an ear lug to support the cross bar 7. The ends of the buckle are rounded as shown at 8, and the periphery of the device is beveled so that as viewed in Fig. 1, the edges of all of the plates are in view.

The metal plate is provided adjacent to each end with a pair of upstanding lugs 9 and 10, respectively, the lugs 9 at one end being inclined in their permanent position, and the lugs 10 at the opposite end being 75 formed at a right angle with the face of the plate. The plate 2 is provided with corresponding apertures to receive the lugs 9 and 10, the apertures 11 being inclined as shown in Fig. 5, and the apertures 12 being 80 wider and provided with an upright inner edge and inclined outer edge, as shown also in Fig. 5.

The apertures 11 and 12 may be formed by first punching similar diagonal holes extending convergently downward toward the center of curvature of the plate. The aperture 12 may then be enlarged and modified by subsequently punching out a part of its inner wall by a vertical punching operation. The 90 lugs on plate 1 may be struck up by a punch-press.

The method of assembling the several parts and securing them together is as follows: The plate 1 is applied to plate 2 by 95 inserting the lug 9 lengthwise into the aperture 11, as shown in Fig. 5, and simultaneously inserting lug 10 into the aperture 12. The lug 10 is then bent outward to a position corresponding substantially with that 100 of lug 9. With the lugs thus disposed, they engage and interlock with the outer edges of their corresponding apertures, as shown in Fig. 7. Suitable filler material 13 is then applied to the unoccupied parts of the apertures 11 and 12, so that the outer surface of plate 2 is smooth and unbroken. The material 13 is preferably in the form of cement formed by dissolving celluloid in a suitable solvent, preferably amyacetate. The next 110 plate 5 of celluloid is then applied to said plate 2 and is secured thereto by means of

acetone applied to the surfaces, and which serves to unite them integrally.

If a third plate of celluloid 3 is used as shown in Fig. 7, this plate is also secured in place by the use of acetone.

In order that the face of the topmost plate may present an attractive appearance, a decorative design made of sheet celluloid is then cemented thereto as shown in Fig. 1, acetone being used as above prescribed. The ornamental attachment may be variously designed, but a monogram or series of letters is considered preferable. When the top plate is white, the appearance of the design may be improved if suitable coloring 14 is applied to the plate surrounding the letters or other decorative device, in order to improve the background and provide a pleasing contrast. This coloring may be applied in the form of pigment mixed with acetone, which causes the coloring material to penetrate indelibly, so that when the acetone evaporates, the coloring material appears to be integral with the celluloid.

Although but one embodiment of this invention and a certain series of detailed steps are herein shown and described, it is to be understood that some of the details of the construction shown and also some of the steps in the process may be modified or omitted, without departing from the spirit of this invention as defined by the following claims.

I claim:

1. An article of manufacture, comprising a metal plate, a sheet of celluloid mounted thereon, fastening means extending from said plate through said sheet and interlocking therewith, and a second sheet of celluloid covering said fastening means and integrally cemented to said first sheet.

2. An article of manufacture, comprising a support having a projecting lug, in combination with a celluloid plate covering said

support and having a perforation in which 45 said lug is secured, and second celluloid plate covering said perforation secured to the first-mentioned plate in a substantially integral manner.

3. A belt buckle, comprising a support 50 having a projecting lug, in combination with a celluloid plate having a perforation in which said lug is secured, means of cement-like character filling the space about said lug and substantially integral with said 55 plate to provide a smooth outer surface, and a second celluloid plate overlying the first-mentioned plate and cemented thereto in a substantially integral manner.

4. The method of applying celluloid ornamentation to a metal body, which consists in fastening a layer of celluloid to the metal by metallic fastening means extending through said layer, then mounting a second layer on the first to cover the fastenings, 60 and causing the two layers to coalesce by means of a volatile solvent.

5. The method of applying a celluloid facing to a metal backing, which consists in providing a pair of celluloid plates of the 70 desired size and form, securing one of said plates to said backing by means of corresponding lugs and apertures provided therefor, and then cementing the other plate to the first-mentioned plate.

6. The method of constructing an article of manufacture which consists in striking up lugs on a metal plate, punching holes in a celluloid plate, applying said plates face to face with said lugs in said holes, bending 80 one or more of said lugs to positively engage the opposite plate, whereby the plates are fastened together, and cementing another celluloid plate to the first one.

Signed at Chicago this 18th day of April, 85
1919.

EDWARD CHAS. BORCHERS.
